(57) **CLAIM**

The ornamental design for a drinking vessel, as shown.

DESCRIPTION

FIG. 1 is a side elevation view of a drinking vessel showing my new design;

FIG. 2 is a cross section view thereof taken along the plane of 2-2 in FIG. 1;

FIG. 3 is an exploded side elevation view thereof on a reduced scale showing the cap portion removed from the bottom portion;

FIG. 4 is a top view thereof, the bottom view being identical;

FIG. 5 is a side elevation view of the bottom portion of the drinking vessel, shown separately for ease of illustration;

FIG. 6 is a top view of the bottom portion thereof;

FIG. 7 is a top perspective view thereof;

FIG. 8 is a bottom perspective view thereof;

FIG. 9 is a side elevation view of the cap portion of the drinking vessel, shown separately for ease of illustration;

FIG. 10 is a top view thereof; and,

FIG. 11 is a bottom view thereof.
